B. HASKELL

TRUCK BOLSTER

Filed Nov. 10, 1926

Broderick Haskell,
McChesney, Brown,

Attorney

UNITED STATES PATENT OFFICE.

BRODERICK HASKELL, OF FRANKLIN, PENNSYLVANIA, ASSIGNOR TO PITTSBURGH STEEL FOUNDRY CORPORATION, OF GLASSPORT, PENNSYLVANIA, A CORPORATION OF PENNSYLVANIA.

TRUCK BOLSTER.

Application filed November 10, 1926. Serial No. 147,499.

This invention relates to bolsters for railway cars and the like and more especially to a fabricated trussed truck bolster made of iron or steel castings and rolled malleable metal.

The objects of the invention are:

First, to construct a fabricated truck bolster of the character indicated which is provided with a recess, pocket or female member of a bearing within and entirely below the upper face or surface of the compression member of said bolster and adapted to receive a coacting male member of a bearing on a cooperating body bolster, said recess, pocket or female member preferably cast or made integral with said compression member and formed as a part of the strut of the bolster.

Second, to construct a fabricated truck bolster in which the compression member is provided with a pocket or female member adapted to receive a coacting male member of a body bolster without the use of a center or king pin, and the bottom of the pocket or female member arranged between the compression and tension members.

Third, to construct a fabricated truck bolster of the character referred to in which the ends of the compression member are rigidly and yet removably clamped to the ends of the tension member and said compression member is also provided with detachable supporting connections with said tension element intermediate its center and ends.

Fourth, to construct a fabricated truck bolster which is provided with a recess, pocket or female member of a bearing within the bolster and entirely below the top surface of the compression member and said compression member with its center strut and tension member are capable of being united into a rigid truss and also able to be taken apart with a minimum of labor and expense.

Fifth, other objects and advantages of construction and arrangement of the several elements comprising the truck bolster will be apparent from the detailed description and manner of assembling the same.

The invention consists of structural characteristics and relative arrangement of ele-

ments which will be hereinafter more fully described and particularly pointed out in the appended claims.

55

In the drawings in which similar reference characters indicate the same parts in the several figures:

Figure 1 is a side elevation of the bolster partly in section combined with its cooperating body bolster.

Figure 2 is a top plan view of the improved truck bolster.

Figure 3 is a section on line III—III of Figure 1.

Figure 4 is a section on line IV—IV of Figure 1, and

Figure 5 is a section on line V—V of Figure 1.

Referring to the drawings, 10 is the compression member which is preferably channel-shaped in cross section having side flanges 11, 11, and a central longitudinal strengthening web 12. Midway between the ends 13, 13, of said compression member 10 is provided an integrally formed pocket or circular recess 14 forming the female member of a center bearing 15, said bearing 15 having an imperforate bottom 16, and an open top 17 substantially flush with the upper face 18 of the compression member 10, as shown in Figure 1. Cast or formed integral with the bottom 16 of the center bearing 15 is provided a depending extension 19 which forms with said bearing 15, the central strut of the truck bolster.

On the underside of the compression member 10 between its center bearing 15 and each of its ends 13, 13, is formed a depending and auxiliary strut 20, having extended and perforated sides 21, 21, to retain a pin 22 with upset ends for purposes to be presently described.

On the upper face 18 of the compression member 10 preferably directly over the auxiliary strut 20 is attached or cast integral therewith a side bearing 23 which cooperates with a corresponding element in the body bolster, as is common in this class of invention.

The ends 13 of the compression member 10 are slightly upturned and each provided on its upper surface with a transverse recess or seat 24, and upper short perforated flanges

or ears 25, 25, and also downwardly extending and perforated flanges 26, 26, as clearly shown in Figures 1 and 5.

27 is the tension member of the truss forming the bolster and is so arranged and bent that its center section engages the bottom of the extension 19 of the central strut and its lateral upwardly inclined ends are seated between perforated sides 21, 21, of the auxiliary struts 20, 20, and are held in place by the pins 22, as clearly shown in Figures 1 and 4. The outer ends of the tension member 27 beyond the auxiliary struts 20, 20, are passed between the lower perforated flanges 26, 26, and turned back near its end and towards the center of the truck bolster and between the perforated ears 25, 25, and pressed into the recess or seat 24 and secured into this position by pins 28, 28, as shown in Figure 5 and at the right end of Figure 1.

29, 29, are chafing plates or guides secured by rivets or bolts 30, 30, to the perforated lower flanges 26, 26, as is commonly provided in this class of inventions.

25 Cooperating with the above described truck bolster 10 is a body bolster 31 having rigidly attached to its under side by rivets 32, or other means, a downwardly projecting hollow male member 33 which is adapted to be seated 30 and supported in the pocket or female bearing member 15 of truck bolster 10 and permitting said body bolster 31 to properly and easily swing through a small arc, as required in this class of railway car appliances, and 35 needs no further disclosure. The bottom and side walls of said hollow projecting male member 33 of the body bolster 31 are preferably provided with openings 34, 34, through which may pass any grease or lubricant stored 40 in said hollow male member 33, said grease or lubricant passing into the center bearing 15 of the truck bolster 10 and between the contiguous side walls and bottoms of the pocket or female member 15 and male member 33, the grease being supplied to the hollow male member 33 through the opening 35 (see Figures 1 and 3) communicating with the interior of the body bolster 31.

From the foregoing disclosure, it will be seen that all the objects and advantages recited in the statement of invention have been fully and efficiently carried out and a fabricated trussed cast or pressed steel truck bolster has been devised in which a recess, 55 well, or female bearing member of a center bearing of any desired depth, and wholly between the compression and tension members of said bolster, can be effected without the use of a king pin cooperating with the body bolster or in any way weakening said bolster, but on the contrary strengthening said bolster with the use of a minimum of metal and cost of manufacture.

While I have shown and described the preferred forms of the invention, it will be read-

ily understood that many changes and arrangements will readily suggest themselves without departing from the spirit of the disclosed invention or changing the function and cooperation of the elements as expressed in the claims.

What I claim is:

1. A fabricated trussed truck bolster comprising a compression member having ends and provided at its center section with an integral depending center strut having formed therein a hollow seat or female member of a bearing having a closed bottom at one end and an open top, a tension member having its center portion engaged by the bottom of the center strut and its outer ends secured to the ends of the compression member.

2. A fabricated trussed truck bolster comprising a compression member having ends and provided at its center section with an integral depending center strut having formed therein a hollow seat or female member of a bearing having a closed bottom at one end, and an open top substantially flush with the upper face of the compression member, a tension member having its center portion engaged by the bottom of the center strut and its outer ends secured to the ends of the compression member.

3. A fabricated trussed truck bolster comprising a compression member having ends and provided at its center section with an integral depending center strut having formed therein a hollow seat or female member of a bearing having a closed bottom at one end and an open top and an auxiliary strut between each of its ends and center strut, a tension member having its center portion engaged by the bottom of the center strut and its outer ends secured to the ends of the compression member, and the portions of the tension member between the center strut and its ends supported or braced by the auxiliary struts.

4. A fabricated trussed truck bolster comprising a compression member U-shaped in cross section and having flanged ends and provided at its center section with an integral depending center strut having formed therein a hollow seat or female member of a bearing having a closed bottom at one end, and an open top substantially flush with the upper face of the compression member, a tension member having its center portion engaged by the bottom of the center strut and its ends seated within and secured to the flanged ends of the compression member.

5. A fabricated trussed truck bolster comprising a compression member having ends and provided at its center section with an integral depending center strut having formed therein a hollow seat or female member of a bearing having a closed bottom at one end, and an open top substantially flush

with the top surface of the compression member, an auxiliary strut depending from and integral with the compression member between each of its ends and center strut, a tension member having its center portion engaged by the bottom of the center strut and each of its sections between its center and ends engaged by an auxiliary strut, and means for rigidly connecting together the ends of the compression and tension members.

6. A fabricated trussed truck bolster comprising a compression member having flanged ends and provided at its center section with an integral depending center strut having formed therein a hollow seat or female member of a bearing having a closed bottom at one end and an open top, an auxiliary strut depending from and integral with the compression member between each of its ends and center strut, a tension member having its center portion engaged by the bottom of the center strut and each of its sections between its center and ends engaged by an auxiliary strut and its ends seated within and secured to the flanged ends of the compression member.

7. A fabricated trussed truck bolster comprising a compression member having double flanged ends and provided at its center section with a depending center strut having formed therein a hollow seat or female member of a bearing having a closed bottom at one end, and an open top substantially flush with the top surface of the compression member, an auxiliary strut depending from the compression member between each of its ends and center strut, a tension member having its center portion engaged by the bottom of the center strut and each of its sections between its center and ends engaged by an auxiliary strut and its ends seated within and secured to the double flanged ends of the compression member.

8. A fabricated trussed truck bolster comprising a compression member having ends H-shaped in construction and provided at its center section with a depending center strut having formed therein a hollow seat or female member of a bearing having a closed bottom at one end, and an open top substantially flush with the top surface of the compression member, an auxiliary strut depending from the compression member between each of its ends and center strut, a tension member having its center portion engaged by the bottom of the center strut and each of its sections between its center and ends engaged by an auxiliary strut, and its bent ends receiving and rigidly connected with the H-shaped cross section ends of the compression member.

9. A fabricated trussed truck bolster com-

prising a compression member having ends with upper and lower flanges and provided at its center section with an integral depending center strut having formed therein a hollow seat or female member of a bearing having a closed bottom at one end and an open top, a tension member having its center portion engaged by the bottom of the center strut and its outer ends secured to the flanged ends of the compression member.

10. A fabricated trussed truck bolster comprising a compression member having ends with upper and lower flanges and provided at its center section with a depending center strut having formed therein a hollow seat or female member of a bearing having a closed bottom at one end, and an open top substantially flush with the top surface of the compression member, an auxiliary strut depending from the compression member between each of its ends and center strut, a tension member having its center portion engaged by the bottom of the center strut and each of its sections between its center and ends engaged by an auxiliary strut, and its outer ends seated between the upper and lower flanges and means for rigidly holding the ends of the tension member seated and between said flanges.

11. A fabricated trussed truck bolster comprising a compression member having recessed outer ends and provided at its center section with an integral depending center strut having formed therein a hollow seat or female member of a bearing having a closed bottom at one end and an open top, a tension member having its center portion engaged by the bottom of the center strut and its outer ends passed under and around into the recesses of the outer ends and toward the center of the truck bolster, and means for securing together the ends of the tension and compression members.

12. A fabricated trussed truck bolster comprising a compression member U-shaped in cross-section and having flanged ends with a recess at its upper side and provided at its center section with an integral depending center strut having formed therein a hollow seat or female member of a bearing having a closed bottom at one end and an open top, a tension member having its center portion engaged by the bottom of the center strut and its outer ends passed between the flanges and under and around into the recesses of the outer ends and toward the center of the truck bolster, and means for securing together the ends of the tension and compression members.

In testimony whereof I hereto affix my signature.

BRODERICK HASKELL.
